Patented January 24, 1874.

Dec. 6 19

Conrad Harris &
Paul W. Goines, of Cincinnati, Ohio.
Letters Patent No. 619. Dated January 24, 1854

The Schedule referred to in these Letters Patent and making part of the same.

To all whom it may concern:

Be it known that we Conrad Harris, and Paul Wm Goines, both of Cincinnati, Hamilton County, State of Ohio, have invented a new and useful design for dining room stoves; and we do hereby declare the following to be a full, and exact description thereof, reference being had to the accompanying drawings, and to the letters of reference, marked thereon, to wit: - Letter a, being a perspective view of the stove.

What we claim as our invention, and desire to secure by Letters Patent, is the figures, scrolls, and mouldings so set forth, in the afored drawings and forming an ornamental design for dining room
